LOCK FOR TRAVELING CASES OR THE LIKE

Filed Dec. 22, 1928

Charles G. Rudderham, INVENTOR:

BY
Emmett & Cook, ATTORNEYS.

UNITED STATES PATENT OFFICE.

CHARLES G. RUDDERHAM, OF NEW ROCHELLE, NEW YORK, ASSIGNOR TO ASSOCIATED MERCHANDISING CORPORATION, A CORPORATION OF NEW JERSEY.

DESIGN FOR A LOCK FOR TRAVELING CASES OR THE LIKE.

Application filed December 22, 1928. Serial No. 29,362. Term of patent 14 years.

To all whom it may concern:

Be it known that I, CHARLES G. RUDDERHAM, a citizen of the United States, and a resident of New Rochelle, in the county of Westchester and State of New York, have invented a new, original, and ornamental Design for Lock for Traveling Cases or the like, of which the following is a specification, reference being had to the accompanying drawing, forming part thereof.

The figure is a perspective view of a lock for traveling cases or the like, showing my new design.

I claim:

The ornamental design for a lock for traveling cases or the like, as shown.

CHARLES G. RUDDERHAM.
